UNITED STATES PATENT OFFICE.

ELLIS D. ALLENSWORTH, OF WAUKEGAN, ILLINOIS.

SPARK-DISTRIBUTER FOR INTERNAL-COMBUSTION ENGINES.

1,282,019.

Specification of Letters Patent.

Patented Oct. 22, 1918.

Application filed October 27, 1917. Serial No. 198,756.

To all whom it may concern:

Be it known that I, ELLIS D. ALLENSWORTH, a citizen of the United States, residing at Waukegan, in the county of Lake 5 and State of Illinois, have invented certain new and useful Improvements in Spark-Distributors for Internal-Combustion Engines, of which the following is a specification.

10 My invention relates to improvements in spark distributors for internal combustion engines.

One of the objects of my invention is to provide a dual distributor, one of which is best adapted for starting the engine, the other being more efficient, simple and suitable for use when and after the engine has attained its normal speed.

Another object of my invention is to provide a speed-responsive device, operable by the engine, whereby to automatically render one or the other of the distributors available in accordance with the variations of speed of the engine.

25 Other and further objects of my invention will become readily apparent, to persons skilled in the art, from a consideration of the following description when taken in conjunction with the drawings, wherein:

30 Figure 1 is a central vertical section of my dual distributor, taken on line 1—1 of Fig. 2.

Fig. 2 is a plan view of the distributor with the cover, or insulating cap removed.

35 Fig. 3 is a section taken on line 3—3 of Fig. 1.

Fig. 4 is a central vertical section taken on line 4—4 of Fig. 2.

Fig. 5 is a perspective view of one of the 40 cam-operated circuit-controlling levers.

Fig. 6 is a similar view of a similar lever adapted to restrain the circuit controlling armature of the electro-magnet.

Fig. 7 is a section taken on line 7—7 of 45 Fig. 2.

Fig. 8 is a diagrammatic view of the circuit.

Fig. 9 is an automatic speed responsive means for switching one or the other apparatus into service.

In all the views the same reference characters are employed to indicate similar parts.

When an engine is running at a relatively 55 slow speed, as when being started, the time interval within which the charge-igniting

spark may be made endures for a longer period of time than when the engine is operating at a greater speed rate. At such times, when the engine is operating slowly, 60 the ignition spark should be made later or retarded in the compression or ignition stroke than when the engine has attained its normal speed.

When an engine is being started it is cold; 65 the compression is not so great and the liquid fuel more viscous and does not so freely volatilize and admix with the incoming air charge, all of which and other deficiencies contribute to sub-normal efficiency 70 and while the mixture is usually rather richer than subsequently in its operation, a better or hotter spark is required to raise the charge to the kindling point, or to ignite it. 75

In my dual igniter one igniting apparatus of the structure may have its cam set ahead of the other cam so as to advance the spark, or to produce the spark earlier in the compression stroke, in point of time, than the 80 cam of the companion apparatus, in the cyclic operation of the engine. The ignition that may advantageously be used when starting the engine is adapted to make a series of sparks in rapid succession, thereby 85 to more perfectly ignite the relatively refractory charge mixture, after which the other more economical igniting apparatus, of the dual igniter, which may have its cam set so as to produce ignition spark at a relatively earlier or advanced time-period in the stroke of the engine, and which makes a single spark for each charge, is manually or automatically brought into effect, in substitution of the previously adverted to apparatus, when the engine has attained normal speed. 90 95

A casing 10, of brass or other suitable material, is provided with a hollow hub 11 and is cut away, as at 12 to provide an aperture 100 for access to the adjustable parts of the device. This aperture is normally closed, by the circumferentially-extending relatively-thin door or plate 13, which is secured to the casing by screws 14. It may contain the 105 name of the manufacturer, patent data, etc., and may be secured to the casing 10 in any other suitable manner. The bearing sleeve 15 is loosely contained within the hollow hub 11 and may be made of Babbitt or other 110 suitable bearing metal, or material, and fitting in the ring is a hollow stud 16 provided

with an axial bore for the cam shaft 17 of an engine, and carrying on its lower end a ring 18 which provides an abutment or rest for the sleeve 15 and the hub 11. The stud 5 16 and the sleeve 18 are secured to the shaft 17 by set screw 19.

In the example illustrated the stud 16 is prolonged vertically and reduced into a relatively small stem 20, upon which are 10 mounted cams 21 and 22, adjustably secured thereto by suitable means, such as a set screw or the like, and mounted upon the upper end of the stem 20 is a commutator arm 23, made of suitable insulating material, and adapted for commutating or distributing the high potential current to the circuits communicating with the spark plugs of the respective cylinders of the engine. If desired the cams 21 and 22 may be a 15 single structure instead of being transversely divided, in which event, of course, they will not be circumferentially adjustable, with respect to each other as above.

A vertical stud 24 is fixed in the casing 10, 20 and on the stud the cam-controlled levers 25 and 26 are spaced apart and are pivoted. The levers are each provided with a roller 27 and 28, respectively, for coöperation with the cam or cams 21 and 22. The lever 25 25 is provided, upon its free end, with an electrical contact 29 which has coöperative circuit association with the relatively stationary, but adjustable contact 30, and which is normally held in contact therewith by a 30 yielding spring 31, which is loosely coiled around the axis of the lever 25 and secured to a fixed stud 32. The contact 30 is fixed to the end of the screw 33, which is threaded into a block of insulating material 34, and 35 held in adjusted position by check nut 35. The block 34 of insulating material, is held in contact with a vertical metal standard 36 that rises from the base 37. The screw 33 passes through a clearance hole in the standard 36, so as not to make electrical contact 40 therewith. The block 34, (Fig. 3) of insulating material is held against the standard 36 by rivets 38, or the like. An electro-magnet 40, provided with a laminated core 41, is secured to the base of the casing 10, 45 as by screws 42.

A standard 43 (Fig. 7) is fixed to the casing 10 and is adapted to support a vibrating armature 44 of the magnet 40. The resilient end 44' of the armature 44 is slotted and secured to the standard 43, by screw 45. By this arrangement the armature may be 50 quickly and easily removed for inspection, by loosening the screw 45 and lifting it from its support. It carries on its outer end an electrical contact 46, for coöperation with the contact 47, which is carried by the adjustable screw 48. This screw is also provided with a check nut 49 by which it 55 may be fixed in adjusted position. These

two screws may each be adjusted through the opening 12 provided in the casing 10 and which is normally covered by the plate 13 and this adjustment may be made while the apparatus is in operation.

70

When the circuit is closed through the armature 44 and the contacts 46 and 47, the armature will be caused to vibrate and make a series of sparks, at the connected spark plugs in a manner to be more specifically hereinafter explained.

75

The casing containing the apparatus described, is covered by a cap or closure 50, preferably made of bakelite or other suitable material, which is radially enlarged at 80 diametric points, as at 51, to provide openings 52 to contain outwardly yielding latch springs 53 that are secured to the casing 10, as at 54, to hold the parts together. The casing cover is also provided with a series 85 of hollow bosses 55. Secured in the bottom of each of the circumferentially arranged bosses and the center boss are contact members 56 which are preferably molded in the cover 50, and which have their bottom surfaces in the same horizontal plane with the top surface of the cavity contained in the cover 50. The center contact member 56 is provided with a rounded extension 57, for association with the commutator member 23. 90

95

Mounted upon the top of each of the contact members 56 or parts thereof, is a spring member 58 for contact association with the separable ball member 59 that is to be connected to the wire 60. The ball members 59 100 are each provided with a stem 61, to which a conductor 62, of each of the wires, is connected. Contact association may be made with spring plates 58, and the balls 59, by pushing the latter into the former. The wire insulation 105 60 will then be contained within the hollow hubs 55, thereby strengthening the insulation of the wires and preventing undue strain upon the contact portions of the wire.

105

Mounted in the free end of the rotatable 110 arm 23 is a contact stud 63, which passes into a vertically extending socket made in the outer end of the arm, and is yieldingly held in its outer position by the spring 64. In contact with the member 63 is a spring 115 plate 65 which is secured to an elevation 66, on the arm 23, and has yielding contact with the rounded extension 57 of the contact piece 56 and which is located in the central hub 55 of the cover 50.

120

The arm 26 (Fig. 2) normally bears against the free end of the armature 44, being yieldingly held in such position to push the free end of the armature 44 toward the magnet 40 so that its contact 46 will not make 125 electrical connection with the relatively stationary contact 47. The spring 67 holds the lever 26 in such position and is more powerful than the resilient end 44' of the armature 44, so that when the cam 22 is 130

in such position as to permit the spring 67 to move the lever 26, the end 26' of the lever will move and hold the armature 44 out of contact, thus breaking the electric circuit, controlled by the electro-magnet 40 and holding it open.

The insulated circuit terminals 70, 71, and 72 are for connecting the device to the respective circuits. Terminal 70 is connected 10 to the stationary insulated contact screw 33 and terminal 71 is connected to the similar screw 48, through the electro-magnet 40. The terminal 72 is also connected to the screw 48 for accommodation of the condenser C'. 15 In Fig. 8 I have shown a schematic arrangement of the circuits wherein B is the battery, C and C' are two condensers, for the respective circuit controlling devices, P is a primary induction coil of the transformer, Sec is the secondary coil of the transformer, SP is the spark plug, and S is the switch.

In starting the engine the switch arm 73 is placed upon the switch button 74. The 25 circuit then will be from ground to the battery B, over the wire 75 to the primary coil P, thence to the arm 73, over the wire 76 to the contact 74, through the wire 77 to the terminals 71 of the device; over the wire 78, 30 through the electro-magnet 40 and by the wire 79 to the contact screw 48, thence to the ground through the armature 44 and the ground wire 80. This will cause the armature 44 to be rapidly vibrated when the contact end 26' of the lever 26, is held away 35 from the armature 44 by means of the cam 22, as shown in the right hand side of the diagram. This will rapidly open and close the primary circuit by the contacts 46 and 40 47, causing a number of sparks to be made at the spark plugs SP, in rapid succession, during the time when the lever 26 is held in the position shown, by the cam 22. As the 45 engine is now being started, the cam 22 having been set somewhat behind the cam 21, so that the sparks thus produced in the cylinder will be made at a later time, with reference to the cyclic operation of the engine, thus more certainly igniting the charge by 50 providing a larger number of hotter sparks for the purpose.

After the engine has attained its normal speed, the arm 73 of the switch may then be shifted to the contact 81, thus permanently 55 breaking the former circuit and causing the current to pass from the arm 73, over the contact 81, from thence by wire 82 to the terminal 70 and by wire 83 to the contact screw 33. The primary circuit is opened 60 between the contacts 29 and 30 only when the cam 21 pushed the lever 25 into position shown in the left hand side of Fig. 8, against the resiliency of the spring 31, thus making only one spark in the cylinder of the engine 65 at each ignition stroke. This is effected

with less current consumption and more simple apparatus. From the contact arm 25 the circuit is closed through the cam to the ground by the wire 84.

In Fig. 9 I have shown how the switch 70 lever 73 may be automatically moved from connection with the contact 74 into connection with contact 81, as the engine attains its speed, by the speed responsive governor 85.

The condensers C and C' bridge the primary circuit spark gaps occurring at the contacts 29 and 30 and the contacts 46 and 47, respectively. The condenser C is connected to the terminal 81 of the switch, by 80 a wire 86; both condensers being connected to the ground G by the wire 87, and condenser C' is connected to the terminal 72, of the device, by wire 88.

The negative terminal of the battery B is 85 connected to the ground by the wire 89.

The secondary induction coil is connected to the wire 75 by wire 90 and to the spark plug, by wire 91, the latter being grounded, as by wire 92.

While I have herein shown and disclosed a specific apparatus, for the purpose of clear disclosure of my invention it will be manifest to persons skilled in the art, that many changes may be made in the general 95 arrangement, configuration and disposition of the parts within the scope of the appended claims.

Having described my invention, what I 100 claim is:—

1. Spark distributing means for an internal combustion engine comprising a casing, means in said casing for producing a series of sparks in the cylinder of an engine during each ignition stroke; means for producing a single spark in the cylinder of said engine during each ignition stroke and means outside of said casing for selecting either spark-producing means.

2. Spark distributing means for an internal combustion engine comprising a casing, means in said casing for producing a series of sparks in the cylinder of an engine during each ignition stroke; means for producing a single spark in the cylinder of 105 said engine during each ignition stroke and mechanically operable means, for automatically selecting either spark producing means.

3. Spark distributing means for an internal combustion engine comprising a casing, means in said casing for producing a series of sparks in the cylinder of an engine during each ignition stroke; means for producing a single spark in the cylinder of 120 said engine during each ignition stroke and speed - responsive means, directly operable by the engine, for automatically changing from one to the other spark producing means.

4. A spark distributor for internal combustion engines comprising two cam-operated levers and a pair of lever-controlled contacts for each lever; a cam for moving said levers; means for vibrating one of a pair of contacts independently of the said levers; a circuit for each said pair of contacts; and a switch for selecting either circuit. 45
5. A spark distributor for internal combustion engines comprising two cam-operated levers and a pair of lever-controlled contacts for each lever; cams for moving said levers; means for vibrating one of a 50 pair of contacts independently of said levers; a circuit for each pair of contacts; a switch for selecting either circuit, and a speed-responsive means for operating said switch. 55
10. 6. A spark distributor for internal combustion engines comprising two cam-operated levers and a pair of lever-controlled contacts for each lever; two adjustable cams, one for moving each said lever; an electro- 60
15. magnet for vibrating one of a pair of said contacts controlled by one of said levers; a circuit for each said pair of contacts, within one of which circuits said electro-magnet is contained; and a switch for selecting either circuit. 65
20. 7. A spark distributor for an internal combustion engine comprising a casing containing two cam-operated levers; a pair of lever controlled contacts for each lever; two independently adjustable cams, one for each 70
25. lever, and an electro-magnet for vibrating one of a pair of contacts controlled by one of said levers; a circuit for each pair of contacts, and a switch for selecting the circuit. 75
30. 8. A spark distributor for an internal combustion engine comprising a casing containing two cam-operated levers; two pairs of contacts, one controlled directly by one 80
- lever and the other pair by an electro-magnet; an electro-magnet for vibrating one of the last mentioned pair of contacts, means for moving the other lever, when released by its cam, to restrain the operation of said electro-magnet and independently adjustable cams, one for each said lever. 85
9. A spark distributing means for an internal combustion engine comprising means for producing a series of sparks in the cylinder of an engine during each ignition stroke; means for producing a single spark in the cylinder of said engine at a different cyclic time during each ignition stroke and means for selecting either means of ignition. 90
10. A spark distributing means for an internal combustion engine comprising means for producing a series of sparks in the cylinder of an engine during each ignition stroke; means for producing a single spark in the cylinder of said engine at a different cyclic time during each ignition stroke; and means to vary the respective cyclic time for initiating said spark-producing means. 95
11. A spark distributing means for an internal combustion engine comprising means for producing a series of sparks in the cylinder of an engine during each ignition stroke; means for producing a single spark in the cylinder of said engine at a different cyclic time during each ignition stroke; means to initiate the operation of the single spark means earlier in the cyclic time of the stroke than the occurrence of the plural sparks, and means for selecting either means of ignition. 100

In testimony whereof I hereunto set my hand in the presence of two subscribing witnesses.
